RAIL BOND

Edward M. Deems, Forest Hills, N. Y., assignor to
 Railroad Accessories Corporation, New York,
 N. Y., a corporation of New York

Application July 11, 1934, Serial No. 734,579

6 Claims. (Cl. 173—280)

This invention relates to conductors, more especially to conductors for connecting the adjacent ends of railway rails, particularly those for use in connection with railway track circuits.

5 It is well understood by those skilled in the railway signalling art, that a track circuit includes an isolated section of the trackway formed by placing insulating joints in each of the lines of rails, and by connecting a battery across the rails at one end, and a relay across the rails at 10 the other end.

It is also well understood that the ordinary rail connecting or fish plates connecting the adjacent ends of the ordinary thirty-six foot sections are 15 not to be relied upon to furnish sufficient conductivity for the electrical energy which flows in the rails from the battery at one end of the section to the relay at the other end thereof. This fact has necessitated a special bonding of each 20 of the adjacent abutting rail ends within the section.

Great difficulties have been encountered in successfully bonding the adjacent abutting rail ends in track circuit sections because provision 25 has to be made for many adverse conditions. A common method is to bond, from one rail web to the adjacent rail web, by means of one or a plurality of conductors of a length somewhat greater than the length of the fish plates. This 30 method of bonding exposes the bonding wires to mechanical injury, in that, they may become entangled with dragging parts from the rolling stock, or may actually get onto the top of the rail, and so be severed by the passage thereover 35 of the wheels of rolling stock. In addition, they are very likely to be damaged by track men while working along the track, particularly when working in and about the rail joint, and more especially when tightening the bolts thereof, or 40 replacing the fish plates with new plates.

A very pronounced difficulty with the old type of bond is, that due to its length and in spite of its size as it may be commercially used, it does not offer a conductivity as great as is desired. 45 The desired conductivity cannot be attained without enlarging the bond to a prohibitive extent.

Attempts have been made to increase the conductivity and decrease the mechanical disadvantages of bonds by applying a bond directly to the rail heads. Such a bond can be very short, as compared with the previously described bond, therefore, for a given diameter have an increased 50 conductivity in that it has less resistance. Such bonds have, in general, been applied to the head

of the rail by electrical or flame welding. Many competent engineers are adverse to applying any considerable degree of heat to the side of the ball of a rail, especially adjacent the end thereof, and this reluctance, considered by many to be well founded, has militated against the use of such bonds.

A further difficulty which has been met with in the type of bond applied directly to the rail heads is that it is particularly exposed to injury by snow ploughs and ballast spreaders. Both of these devices, and especially the ballast spreader, have parts which extend below the top surface of the head of the rail on the outside thereof. These parts, due to the swaying of the vehicle, 15 come in contact with the head of rail bonds and destroy them.

Attempts have been made to attach bonds to rail heads by drilling a cavity in the rail head and attaching the bond to a plug driven into the 20 cavity. A difficulty with this type of bond arises from the fact that it is necessary to drill a relatively deep hole in the head of the rail. This hole penetrates what might be called the active load bearing cross-sectional area of the head and 25 to that extent weakens the rail head.

In my copending application Serial No. 538,943, filed May 21, 1931, I have illustrated, described and claimed a type of bond for attachment to rail heads. This type of bond obviates many of 30 the defects of the types of bonds heretofore used and has many desirable virtues especially in that the cavity which must be formed in the head of the rail for the reception thereof is so shallow that it does not penetrate the active load sustaining cross-section of the rail. By reason of 35 this fact, incipient cracks which may develop in the rail head are not afforded an easy opportunity to spread by reason of the cavity formed for the reception of the head of the rail bond, as 40 that cavity does not closely approach the point of origin of the cracks.

I have discovered, in practice, that the type of bond illustrated and described in my copending application, hereinbefore referred to, has a weakness in that it is subject to injury at the junction line of the surface in which the cavity is produced and the bond. This weakness has been cured by me through the adoption of the structure of bond as shown by my copending application Serial No. 600,595, filed March 23, 1932, now Patent No. 1,945,480 granted January 30, 1934.

A principal object of this invention is to provide a bond of the type illustrated, described and 55

claimed in my copending applications hereinbefore mentioned, of such construction that it will have the desirable virtues of the specific constructions of the prior application, and in addition will have desirable virtues not possessed by the prior forms.

A further object of this invention is to provide a bond of the type specified which will be of such construction that it will be adapted for connection in cavities formed in a rail head or other place having that difference in diameter which may well occur in practice due to the difference in the drills used, either as to their original size or because of the particular grinding thereof.

15 A further object of the invention is the production of a bond of the type specified which will be of such construction that it may be more readily removed from the cavity in the rail head or other place in which it is positioned.

20 Other objects and advantages will appear as the description of the particular physical embodiments selected to illustrate the invention progresses, and the novel features will be particularly pointed out in the appended claims.

25 In describing the invention in detail and the particular physical embodiments selected to illustrate the invention, reference will be had to the accompanying drawing, and the several views thereon, in which like characters of reference designate like parts throughout the several views, and in which:

Figure 1 is a fragmentary vertical sectional view of a portion of rail head with a portion of a bond embodying my invention in place therein; Fig. 2 is a fragmentary view illustrating a side elevation of the arrangement as shown by Fig. 1; Fig. 3 is a part section, part elevation illustrating the initial position of the plug portion of my bond as it is being driven into a cavity in a rail head; Fig. 4 is a view similar to Fig. 1 but showing a modified form; Fig. 5 is a side elevational view showing the form illustrated by Fig. 4; Fig. 6 is a view similar to Fig. 3 but showing the form of bond illustrated by Fig. 4; Fig. 7 is a view similar to Fig. 1 but illustrating a further modified form of bond; Fig. 8 is a side elevational view similar to Fig. 2 of the bond as illustrated by Fig. 7; Fig. 9 is a view corresponding to Fig. 3 but showing the bond illustrated by Fig. 7; Fig. 10 is a view corresponding to Fig. 1 but illustrating a modified form; Fig. 11 is a side elevation corresponding to the side elevation, Fig. 2, but showing the bond as illustrated by Fig. 10; Fig. 12 is a view corresponding to Fig. 3 but illustrating the bond of Fig. 10; Fig. 13 is a cross-sectional view of the bond as shown by Fig. 10 but in a plane at a right angle to the plane of section of Fig. 10.

In Fig. 1 a fragment of a rail head 1 is shown. This rail head fragment 1 as shown in Fig. 1 has a cavity 2 formed therein. This cavity is formed, as shown, by using the usual form of drill and consequently it will vary in its diameter. High grade drills made by reputable manufacturers are, of course, extremely close to size, but if they are not ground properly they will drill over-size holes, consequently, the cavity 2, substantially circular in outline, may have a diameter corresponding exactly to the desired diameter or it may be larger.

70 In order to provide the plug portion, as 3, of a bond which will properly fit into cavities made in rail heads, notwithstanding the usual variation in sizes thereof, applicant has provided the plug portion 3 of a bond with an over-size portion. 75 This over-size portion in Fig. 3 is the frustum of

a cone, designated as the entering head 4. This head has a top face 5 which has a diameter preferably much less than the diameter of the cavity 2 and has a base 6 which is larger in diameter than the diameter of the cavity 2. The cylindrical body portion 7 is preferably a shade less in diameter than the diameter of the cavity 2. A driving head 8 is attached, as integrally, to the cylindrical portion 7.

The plug 3 is formed of metal. It is formed of 10 a metal which will flow somewhat under pressure. It is preferably formed of soft copper, although mild steel works very satisfactorily, in any event, the metal should be somewhat plastic when cold. When a plug, such as 3, of substantially the dimensions as shown is positioned in the opening of a cavity 2, and then blows are applied to the head 8 the corners 9 of the frustum of a cone 4 are displaced and caused to flow along the cylindrical portion 7 of the plug, so that, as the plug 3 15 enters into the cavity 2 it just fits the cavity 2 and is thereby guided so as to align its longitudinal axis with the longitudinal axis of the cavity 2, and when the top 5 of the frustum of the cone contacts with the base wall 10 of the cavity 2, it 20 spreads out and fills the space so that if the diameter of the cavity 2 closely approximates the diameter of the cylindrical portion 7 of the plug 3, the final position of the parts will be as shown in Fig. 1, that is, the plug 3 will completely fill 25 the cavity 2, as illustrated by Fig. 1, with a shoulder 11 spaced a slight distance from the edge of the rail 1.

The space between the side of the rail 1 and the shoulder 11 affords an opportunity to place 30 a two pronged tool between the rail and the shoulder of the plug and by a leverage action pull the plug out of the cavity. This is often necessary because of the destruction of some part of the bond.

40 As is well understood the plug portion 3 with its associated head 8 is always used in pairs, one being positioned in one rail head, the other being positioned in an adjacent rail head, the two being connected by an electrical conductor. This is well known in the art and is fully shown in my copending application Serial No. 538,943 filed May 21, 1931 and in application Serial No. 647,308, filed December 15, 1932.

In the case of the present plug 3, provision is 50 made for the conductor to the other plug of the pair by forming a slot 12 in the driving head and inserting therein laminae 13 which may be held tightly in position in any usual or approved manner as by rivets 14 and 15 and/or by soldering or 55 by welding.

Although applicant's plug 3 is suitable for a standard size cavity 2, it also is suitable for an over-size cavity 2, because applicant always makes the base 6 of the frustum of a cone 4 of greater 60 diameter than any diameter of the cavity 2 which occurs even with the most unskillful grinding of drills which will occur in practice. When the cavity 2 is sufficiently over-size, the cylindrical portion 7 will not contact entirely along the wall 65 of the cavity 2. This is not a defect, however, but in fact is a virtue, so much so, that applicant prefers to form his plug in such manner that it will give such result in all cavities regardless of their diameter and is the basis upon which the 70 other plugs, shown in Figures 4 to 13 inclusive are constructed.

In Fig. 6 a plug 16 is shown. This plug terminates with the frustum of a cone 17, but between the base 18 of the cone and the cylindrical 75

portion 19 of the plug there is a cylindrical portion 20 larger in diameter than the cylindrical portion 19 of the plug, or to put it in another way, the cylindrical portion 19 of the plug is 5 smaller in diameter than the cavity 2. When this plug is driven the final result is as shown by Fig. 4, that is, the plug bears upon the circular inside surface of the cavity 2 from the line 21 to the line 22 so that the edge 23 of the cavity is not in 10 contact with the plug. This is advantageous, because the point of contact between the edge 23 of the cavity and the plug is a line of weakness in the plug arising from the constant vibration to which the plug is subjected in practice. 15 It is at this point that the plugs may break off. By separating the edge 23 from the plug, the breakage is obviated. Not only is the breakage obviated, but by making the parts of such dimensions that the length of the surface between the 20 lines 21 and 22 is as desired, any particular firmness of hold may be obtained, that is, a plug may be in contact with such an amount of surface of the cavity 2, that it is very difficult to withdraw the plug, or it may be in contact with such a 25 small amount of surface of the cavity 2, that it may be withdrawn fairly readily. This difference in action may be easily regulated by regulating the length and diameter of the cylindrical portion 20 of the plug.

30 In the form of plug as shown by Figs. 4, 5 and 6, the conductor to be attached to the companion plug is fitted into a central bore 24 of the plug and lies in a slot 25 of the head. When the plug is driven into the cavity 2, the walls of the plug 35 are squeezed inwardly and firmly hold the conductor 26, making intimate mechanical and electrical contact therewith.

In Figs. 7, 8 and 9 another modified form of plug is shown. This plug 27 may be constructed, 40 insofar as its conical head 28 and cylindrical portion 29 is concerned, just exactly like the plug in Fig. 6 has its corresponding parts 17 and 20 formed, but the conductor 30 for connection to the companion plug is positioned in a longitudinal 45 slot 31 and a transverse slot 32. When the plug 27 is driven, the walls of the plug are squeezed inwardly and make intimate mechanical and electrical contact with the conductor 30 which like the plug is usually made of fairly soft copper.

50 The form of bond shown in Figs. 10, 11 and 12 is, as regards the cone shaped end, the cylindrical portion adjacent thereto and the driving head, the same as the cone shaped end 17, the cylindrical portion 20, and the driving head of the plug 55 of Fig. 6, but the conductor 33 connecting the plug to the companion plug lies in two parallel slots longitudinal of the plug, one of which is designated 34 and the other of which is designated 35. When this form of plug is driven into a cavity as 2, the plug acts just as does the plug 16 of Figure 6 and the walls thereof collapse somewhat and make intimate mechanical and electrical contact with the portions 36 and 37 of the conductor 33, and in addition the conductor 33 at the portion 38 is forced into intimate mechanical and electrical contact with the body of the rail head 1.

Each of the forms of plugs shown in Figs. 4 to 13 inclusive is provided with a driving head, that is, the portion 39 in Fig. 4; the portion 40 in Fig. 7; and the portion 41 of Fig. 10. Each of the driving heads forms a shoulder as 42 in Fig. 4; 43 in Fig. 6; and 44 in Fig. 10. Between the side of the rail 1 and the shoulder on the plug a two pronged tool may be positioned so as to straddle 18 the cylindrical portion such as 19 of Fig. 6 and

then be used as a lever to withdraw the plug from the cavity in which it has been pressed.

The plugs of applicant's invention are suitable for many situations where an electrical conductor must be mechanically and electrically attached to a metal body. They are peculiarly adapted for connection of an electrical conductor to railway track structures such as rails, switches, fish plates and the like, but they are particularly valuable for use in bonding railway rails for track circuit 10 purposes where the highest possible conductivity at the lowest possible cost is desired, and they are especially valuable in use as that type of bond known, as rail head to rail head bond, in which the complete bond is not much over six inches 15 in length and preferably not over about four and one half inches in length and in which the plugs are inserted in cavities drilled in the side of the rail head, as illustrated in my prior application hereinbefore referred to. They are particularly 20 valuable where the cavity, as 2, is formed in the substantially non-load bearing cross-section of the rail, as explained in my application Serial No. 647,308, filed December 15, 1932, that is, where all of the material to the left of the line 45 of Fig. 25 1 is substantially non-load bearing, so that the cavity 2 is all or substantially all in that portion of the rail head which is substantially non-load bearing so that the formation of the cavity 2 does not conduce to the formation of incipient cracks. 30

Although I have particularly described several particular physical embodiments of my invention and explained the operation, construction and principle thereof, nevertheless, I desire to have it understood that the forms selected are 35 merely illustrative but do not exhaust the possible physical embodiments of the idea of means underlying my invention.

What I claim as new and desire to secure by Letters Patent of the United States, is:

1. A plug for electrically and mechanically attaching a conductor to a metal body, the plug formed of a somewhat plastic metal, and formed with an entering head and with a driving head connected by a body portion substantially cylindrical and less in diameter than the diameter of the driving head or the diameter of the largest portion of the entering head, said entering head comprising a flaring portion with the smallest diameter at the tip end of the entering head and 50 the largest diameter adjacent the body, said largest diameter portion of the flaring head being greater in diameter than the cavity into which the plug is to be driven whereby a portion of the flaring head will be caused to flow along the body 55 portion upon driving the plug into a cavity, said driving head providing a shoulder whereby a means is provided for removing the plug from a cavity by the insertion of a tool between the body in which the cavity is formed and the shoulder. 60

2. In a plug for insertion into a cavity in a body for making intimate mechanical and electrical contact between the body and a conductor, having a substantially cylindrical body portion somewhat less in diameter than the cavity into which 65 the plug is to be placed; a cylindrical portion of somewhat larger diameter than the body portion adjacent the end of the body portion; a flaring portion adjacent the larger diameter cylindrical portion having its largest diameter adjacent the 70 cylindrical portion and its smaller diameter at the end of the plug; a driving head on the other end of the body portion, said driving head being of larger diameter than the cylindrical portion thereby affording a shoulder; said parts all formed 75

with a bore therethrough and said head formed with a slot communicating with the bore whereby a metallic conductor may be positioned therein for connection by the plug.

5. 3. In a plug for insertion into a cavity in a body for making intimate mechanical and electrical contact between the body and conductor, having a substantially cylindrical body portion somewhat less in diameter than the cavity into which the plug is to be placed; a cylindrical portion of somewhat larger diameter than the body portion adjacent the end of the body portion; a flaring portion adjacent the larger diameter cylindrical portion having its largest diameter adjacent the cylindrical portion and its smallest diameter at the end of the plug; a driving head on the other end of the body portion, said driving head being of larger diameter than the cylindrical portion thereby affording a shoulder; and means for connecting an electrical conductor to said plug.
10. 4. In a plug for insertion into a cavity in a body for making intimate mechanical and electrical contact between the body and a conductor, having a substantially cylindrical body portion somewhat less in diameter than the cavity into which the plug is to be placed; a cylindrical portion of somewhat larger diameter than the body portion adjacent the end of the body portion; a flaring portion adjacent the larger diameter cylindrical portion having its largest diameter adjacent the cylindrical portion and its smallest diameter at the end of the plug; a driving head on the other end of the body portion, said driving head being of larger diameter than the cylindrical portion thereby affording a shoulder; said plug being formed with two parallel orifices longitudinal thereof connected by a transverse slot 20 in the flaring portion whereby a conductor may be connected thereto.
15. 5. In a plug for insertion into a cavity in a body for making intimate mechanical and electrical contact between the body and a conductor, having a substantially cylindrical body portion somewhat less in diameter than the cavity into which the plug is to be placed; a cylindrical portion of somewhat larger diameter than the body portion adjacent the end of the body portion; a flaring portion adjacent the larger diameter cylindrical portion having its largest diameter adjacent the cylindrical portion and its smallest diameter at the end of the plug; a driving head 15 on the other end of the body portion, said driving head being of larger diameter than the cylindrical portion thereby affording a shoulder; said plug being formed with two parallel orifices longitudinal thereof connected by a transverse slot 20 in the flaring portion whereby a conductor may be connected thereto.
20. 6. In a plug for driving into a cavity for connecting a conductor to a metal body in a circular cavity formed in the metal body which consists of a substantially cylindrical body smaller in diameter than the diameter of the cavity, and having a head thereon at the end first entering the cavity having in part a diameter greater than the diameter of the cavity, and such portion being of such 30 length longitudinally of the plug that when the plug is driven into the cavity it will contact the circular portion thereof for only a portion of its distance; and means for connecting the conductor to the plug.
25. 35.

EDWARD M. DEEMS.
